UNITED STATES PATENT OFFICE.

COLONEL L. LARRABEE, OF GLENVILLE, NEW YORK.

COMBINED FILING AND EXHIBITING DEVICE.

Application filed September 1, 1925. Serial No. 53,843.

This invention relates to a combined filing and exhibiting device, designed primarily for use in connection with photographs of the kodak type and is termed a kodagraph, but although the device is designed primarily for use in connection with photographs, yet it is to be understood that it can be employed for any purpose for which it is found applicable, such as an advertising directory or scrap-book, as well as for filing and exhibiting printed, written or newspaper clippings and cooking recipes, and the invention has for its object to provide, in a manner as hereinafter referred to, a device for conveniently filing, as well as exhibiting any one or a plurality of filed photographs, objects, clippings, or other matter, and further for retaining the same from accidentally shifting when moved to exhibited position.

Further objects of the invention are to provide, in a manner as hereinafter set forth, a combined filing and exhibiting device for the purpose referred to, which is simple in its construction and arrangement, strong, durable, compact, capable of being stored in a small space when not used, thoroughly efficient in its use, conveniently operated for exhibiting purposes, and inexpensive to manufacture.

With the foregoing and other objects in view, the invention consists of a novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views—

Figure 1 is a sectional elevation of a filing and exhibiting device in accordance with this invention.

Figure 2 is a longitudinal sectional view thereof.

Figure 3 is a section on line 3—3, Figure 2.

Figure 4 is a section on line 4—4, Figure 2, upon an enlarged scale and partly broken away.

Figure 5 is a section on line 5—5, Figure 2.

Figure 6 is a section on line 6—6, Figure 2.

Figure 7 is a section on line 7—7, Figure 1.

A filing and exhibiting device, in accordance with this invention, comprises a cabinet preferably of rectangular contour, and which includes a body section and a top section referred to generally by the reference characters 1, 2, respectively. The body section is of greater height than the top section and the latter is hinged to the frame, as at 3. The sections 1 and 2 are provided with a co-acting means to provide a key operated lock, as at 4 for locking the section 2 to the section 1.

The section 1 is formed of a pair of end walls 5, 6, a front wall 7, a rear wall 8, and a bottom 9. Corner posts 10 are arranged against the inner face of said walls and suitably secured thereto. The corner posts are mounted on the bottom 9 and are of the same height as the height of the side and end walls of the section 2. Secured to the inner face of the front wall 7, as well as to the inner face of the rear wall 8, is a pair of spacing members 11. The members of each pair are spaced a substantial distance from each other and each of said members is arranged in close proximity to the corner posts 10. Each of the spacing members is rabbeted as at 12. The width and length of the bottom 9 is such as to project laterally from the front, rear, and end walls when the body section 1 is set up.

The top section 2 comprises a rectangular body portion 13 which seats on the body section 1 when the top section is in closed position. Secured upon the top edge of the body portion 13 is a rectangular frame 14 of a width and length to project laterally from the front, rear and ends of the body portion 13. The opening formed by the frame 14 is indicated at 15 and extending across said opening 15, as well as anchored in the inner side and end edges of the frame 14 is a transparent member 16, preferably formed from a sheet of glass. Mounted on the frame 14, for the purpose of closing the opening formed by the latter, is a closure member 17 of a width and length greater than the opening 15. The closure member 17, at its rear, is hinged to the frame 14, as at 18, and the frame 14 at the front

thereof, carries a shiftable latch 19 adapted to overlap the closure member 17 for the purpose of locking it in closed position with respect to the opening 15 formed by the frame 14. The upper face of the closure member 17 is provided with a handle or grip 20.

The front wall 7, of the body section 1, is provided with a pair of openings 21, 22 positioned to align with each other and arranged at the longitudinal center of said wall 7. Positioned within each of said openings, is a flanged bearing collar 23 having its flange 24 engaging the outer face of the wall 7.

Mounted within the cabinet is a supporting frame consisting of two pairs of vertically disposed uprights, a pair of longitudinally extending bars and a horizontally disposed combined brace and coupling member. The uprights of one pair are indicated at 25, 26, and are arranged in spaced relation and extend from the bottom 9 to a point in proximity to the frame 14. The uprights of the other pair are indicated at 27, 28, are arranged in spaced relation and extend from the bottom 9 to a point in proximity to the frame 14. The uprights of each pair are of the same height and one pair of uprights is arranged a substantial distance and in alignment with the other pair of uprights. The longitudinally extending bars are indicated at 29, 30 and are positioned against the inner faces of the uprights of said pairs intermediate the ends thereof. The bar 29 has its ends secured by the holdfast devices 31 to the uprights 25 and 27 and the bar 30 has its ends secured by the holdfast devices 32 to the uprights 26 and 28. As each of said bars is of the same construction, but one will be described, as the description of one will apply to the others. Each of said bars is provided at its transverse center with an opening 33 and in proximity to one end with an opening 34 and is furthermore provided in proximity to its other end with an angle-shaped slot 35 formed of a vertical and a longitudinal portion arranged at the upper end of the vertical portion and disposed at right angles thereto. The vertical portion opens at the lower edge of the bar and the other portion of the slot is arranged at the longitudinal center of the bar. The function of the angle-shaped slots 35 will be presently referred to. Each of the uprights, at the upper end thereof, is formed with an inwardly extending combined guide and stop lug 36 for a purpose to be presently referred to.

The horizontally disposed combined brace and coupling member is indicated at 37 and which extend through the openings 33 formed in the bars 29 and 30, as well as projects laterally from each of said bars and

its projecting ends are peripherally threaded. The ends of the member 37 also extend through a pair of vertically disposed supports 38, one positioned exteriorly of and abutting against the bar 29 and the other positioned exteriorly of and abutting against the bar 30. The member 37 carries on each of its ends a securing nut 39 for connecting said member and bars 29, 30, together, as well as for clamping the supports 38 against the outer face of the bars 29, 30. The upper end of each of the supports 38 is formed with an inwardly extending yoke 40 which provides a coupling means for a controlling spring to be presently referred to.

The frame further includes a pair of longitudinally extending top bars which are indicated at 41, 42 and each of which is formed with a series of spaced openings 43 at the longitudinal center of the bar. The top bars 41 and 42 have their end terminal portions project from the upper ends of the standards 25, 26 and the standards 27, 28 and engage against the members 11. The bar 41, as well as the bar 42, between its transverse center and each end, is formed with transversely extending slots and which are indicated at 44. Extending into the slots 44 of the bar 41 are the lugs 36 carried by the standards 25, 27 and extending into the slots 44 of the bar 42 are the lugs 36 of the standards 26 and 28. By this arrangement the top bars 41 and 42 are slidably mounted upon the upper ends of the uprights or standards. Each of the top bars, at a point between its transverse center and slot 44, has secured thereto as well as depending therefrom, an inverted L-shaped retaining member 45 which is arranged at the inner face of the bar and depends below the bottom edge of the latter. The arrangement of the lug 36 with respect to a top bar is shown in Figure 6 and the construction and arrangement of the retaining member 45, with respect to a top bar, is shown clearly in Figure 5.

The top bars are resiliently supported, and normally in an upwardly projected position, and to provide for such arrangement, each of the top bars has associated therewith a spring of concave curvature as indicated at 46. Each of said springs is formed with a concave intermediate portion and a pair of straight end portions 47 which bear against the bottom edge of a top bar, see Figure 5, and said end portions are retained against the inner faces of the pair of uprights or standards through the medium of the members 45 carried by each of the top bars. The intermediate portion of the spring 46 extends through the yoke 40, see Figure 7.

Arranged within and supported by the frame positioned within the cabinet is a pair

of reels, referred to generally by the reference characters 48 and 49, and the latter is removable. Each of said reels consists of a hub 50, a pair of circular heads 51 and a shaft 52 which extends through the heads 51 and hub 50 and is fixedly secured to the hub and heads. The shaft 52 projects a substantial distance from each head 51 and one of the projecting ends of the shaft 52 10 has a polygonal-shaped end terminal portion 53.

The shaft 52 of the reel 48 is journaled in the openings 44 of the bars 29, 30 and the polygonal-shaped end terminal portion 53 of 15 said shaft extends into the collar 23 mounted in the opening 21 of the wall 7, and said collar is spaced from said end 53 so that a crank handle 54 can be inserted in the collar and engaged with the terminal portion 20 53 for the purpose of revolving the reel 48 to wind up a flexible carrier to be presently referred to.

The shaft 52 of the reel 49 is removably mounted in the angle-shaped slots 35 and is 25 retained in the longitudinal portions of said slots, through the medium of holding springs 55 carried by the bars 29 and 30 and bearing against the projecting ends of such shaft. The polygonal-shaped portion 53 of the shaft 30 52 extends into the collar 23 mounted in the opening 22 so that the shaft 52 of the reel 49 can be operated when desired, by the crank handle 54, for the purpose of winding the carrier, to be presently referred 35 to, on the reel 49. When the reel 49 is revolved the carrier is wound off the reel 48 and on the reel 49 and when the reel 48 is revolved by the crank handle 54 the carrier is wound off the reel 49 and on to the 40 reel 48. When the crank handle is used it is removably connected with the polygonal-shaped end of the shaft of either of the reels.

The openings 43 and the top bar 41 align 45 with the openings 43 in the top bar 42 and in each pair of aligning openings is journaled the spindle 56 of a combined idler and supporting roller 57.

A flexible carrier is employed to which is 50 secured the photographs 58 or other objects. The photographs 58 are secured on the upper face of the flexible carrier and the latter is indicated at 59 and is formed from a web of any suitable fabric and the carrier 58 55 winds on and off either of the reels. The rollers 57 support the carrier 59 below the transparent plate 16 and the springs 46 shift the top bars 41 upwardly so that the photographs 58 will be brought in snug engagement with respect to the lower face of the transparent plate 16 and when so positioned, the force of the springs 46, will prevent the accidental shifting thereof. The rollers 57, are resiliently supported, and are 60 constantly pressed upwardly by the sup-

porting springs 46 so that the photographs or other objects fixed to the carrier will be pressed against the lower face of the transparent panel or sheet 16 regardless of the thickness of the photograph and said spring 70 controlled rollers act as a brake, so that when the photographs are moved directly under the glass they will remain motionless until one of the reels is revolved. The rollers 57 furthermore prevent the carrier from 75 sagging whereby the photograph will be held tightly against the transparent panel so that it will be visible throughout.

It is thought the many advantages of a combined filing and exhibiting device, in 80 accordance with this invention, can be readily understood, and although the preferred embodiment of the invention is as illustrated and described, yet it is to be understood that changes in the details of construction can be had which will fall within 85 the scope of the invention as claimed.

What I claim is;

1. A device for the purpose set forth comprising a receptacle provided at its top with a transparent panel, a series of supporting rollers positioned in proximity to said panel and within the receptacle, a pair of revolute reels below said rollers, a flexible carrier winding off of one of said reels and on to the other and having a length thereof supported by and interposed between said rollers and transparent panel, supporting means for said reels, said means including a pair of spring controlled shiftable bars for 90 resiliently and revolvably supporting said rollers, and controlling springs of concave curvature for said bars, said springs connected to each side of said means and having their ends slidably coupled with said 95 bars.

2. A device for the purpose set forth comprising a receptacle formed of an upper and lower section hinged together, said upper section consisting of a frame and a 100 transparent panel closing the opening formed by the frame, a concealing member for the panel hinged to the frame, means for latching said member in concealing position, and a handle carried by said member. 105

3. In a device for the purpose set forth, a receptacle having its top provided with a transparent panel, a removable supporting frame including a pair of spring controlled shiftable bars at the top thereof and further 110 including a pair of side bars positioned intermediate the top and bottom thereof, controlling springs for said top bars slidably coupled therewith and further connected to said intermediate bars, a pair of reels revolvably mounted in said intermediate bars adjacent their ends, one of said reels being removable from said intermediate bars, a flexible carrier winding off of one of said 115 reels and onto the other, a series of rollers 120

revolvably mounted in the top bars for supporting a length of said carrier in proximity to said panel, and means for operating one of said reels.

5. In a device for the purpose set forth, a receptacle having its top provided with a transparent panel, a removable supporting frame including a pair of spring controlled shiftable bars at the top thereof and further 10 including a pair of side bars positioned intermediate the top and bottom thereof, controlling springs for said top bars slidably coupled therewith and further connected to said intermediate bars, a pair of reels revolvably mounted in said intermediate bars 15

adjacent their ends, one of said reels being removable from said intermediate bars, a flexible carrier winding off of one of said reels and onto the other, a series of rollers revolvably mounted in the top bars for supporting a length of said carrier in proximity to said panel, means for operating one of said reels, and a pair of flat springs carried by said intermediate bars and coacting with one of said reels for retaining said removable reel in position in said intermediate bars. 20 25

In testimony whereof, I hereby affix my signature hereto.

COLONEL L. LARRABEE.
